UNITED STATES PATENT OFFICE.

ALF SELROD, OF CHICAGO, ILLINOIS.

COMBINED COMPRESSOR AND CONDENSER.

Application filed August 15, 1919. Serial No. 317,723.

To all whom it may concern:

Be it known that I, ALF SELROD, a citizen of the United States, residing at Chicago, in the county of Cook and State of Illinois, have invented a new and useful Improvement 5 in Combined Compressors and Condensers, of which the following is a specification.

My invention relates to an improved form 10 of compressor, adapted for refrigerating purposes, in which a condenser is located in the same casing as the compressor and I preferably provide in connection with this construction a common means for cooling 15 both the compressor and condenser.

My invention is particularly applicable to small compressor units where the condenser capacity required for the operation of the system is not large, such for example, 20 as small refrigerating units for domestic purposes. My invention provides a compact construction which is desirable for small units of the kind referred to, the only parts outside of the compressor unit which 25 are required for the operation of the system, being an expansion valve and the refrigerating coils. Any form of motor which is convenient may be employed to drive the compressor.

30 My invention will best be understood by reference to the accompanying drawings showing a preferred embodiment thereof, in which—

Fig. 1 is a vertical, central, sectional view 35 through the compressor taken transversely of the crank shaft thereof,

Fig. 2 is a similar sectional view through the compressor longitudinally of the crank shaft thereof,

40 Fig. 3 is a sectional view of the parts shown in Fig. 1 taken along the line 3—3, and

Fig. 4 is a sectional view of the parts shown in Fig. 2 taken along the line 4—4.

45 Similar numerals refer to similar parts throughout the several views.

As shown in the drawings my improved construction consists of a casing 10, preferably of cast iron, having a central bore 11 50 forming the compressor cylinder, from the lower portion of which an inlet passageway extends for receiving the piping connecting with the expansion or refrigerating coils. A piston 13 is located in the cylinder 11 and connected with the crank shaft 14 by a con-

necting rod 15. The piston 13 is hollow above its lower end and of skeleton construction permitting free communication between the passageway 12 and the inside of the piston at all times and the upper end 60 of the piston is provided with an intake valve 16 which permits the gas to pass readily through the piston into the cylinder 11 during each down stroke of the piston. During each up stroke of the piston the 65 valve 16 is closed and the gas contained in the cylinder 11 is compressed. The upper end of the cylinder is counterbored to form a seat for the outlet valve 17 which is held in place on said seat by a spring 18 contained within said valve between it and the head 19 used to close the upper end of the cylinder.

The casing 10 has formed in it around the cylinder 11 an annular cored receptacle or 70 compartment 20 forming a water jacket for the cylinder and around this compartment said casing has formed in it a second similar recess or compartment 21 forming the condenser, around which the casing contains 80 a third recess or compartment 22 forming an outer water jacket for the condenser.

The head 19 besides enclosing the upper end of the cylinder 11 also encloses the upper ends of the water jacket 20 and the condenser 21 and is held in place by suitable screws as indicated. The outer wall of the casing 10 extends upwardly above the head 19 and is enclosed by a second head 23 so that the outer water jacket 22 extends upwardly and between the heads 19 and 23.

The head 19 has formed centrally thereon an upwardly extending boss 24 containing a valve 25 for controlling communication between an opening 26 into the upper end of 95 the cylinder 11 and a passageway 27 formed in the head 19 and connecting with the upper portion of the condensing compartment 21. As a result of the construction described, when the valve 25 is turned by means of its 100 projecting stem 28 any desired degree of communication between the cylinder 11 and the condenser 21 may be established, or said communication may be entirely interrupted. The upper portion of the condenser 21 is 105 provided with a passageway 28 extending to the outside of the casing 10 for connection by suitable fittings with a pressure gauge 29 and a purging valve 30. The valve 30 is opened occasionally to remove air from the 110

compressing and condensing system. The lower portion of the condenser communicates by a passageway 31 with the outside of the casing 10 from which point by suitable connections and fittings the liquid resulting from condensing the compressed gas is drawn from the device and forced by the pressure exerted upon it by the compressor through a suitable expansion valve into the expansion or refrigerating coils where the liquid expands into gaseous form, the return pipe from the expansion coils being connected with the intake passageway 12 above described. The expansion valve and expansion coils are not shown as they form no part of the present invention, their operation being the same as in refrigerating systems well known in the art.

The lower portion of the condensing compartment or receptacle 21 is preferably provided, as shown in Figs. 1 and 4 with a downwardly extending pocket 32 to collect the oil which may be carried over from the compressor with the compressed gas into the condenser. The lower portion of the pocket 32 is connected by suitable pipe fittings 33 and a controlling valve 34 with the crank case 35 so that the oil collected in said pocket may be drawn off from time to time and returned to the crank case. The crank case 35 is preferably wholly enclosed and contains a quantity of lubricating oil through which the lower end of the connecting rod 15 passes during operation of the compressor to lubricate the moving parts by the resultant splashing of the oil. A connection 36 with the lower part of the crank case is provided to receive suitable fittings to retain the oil in the crank case and drain the oil therefrom when it is necessary to renew the used oil.

As indicated in Fig. 2 the lower portion of the water jacket 20 communicates with a passageway 37 extending to the outside of the casing 10 by which the cooling and condensing water may be supplied to said water jacket and the upper portion of said water jacket communicates on the other side of the device by a passageway 38 with the water jacket 22 from which the water discharges through an opening 39 in the casing. The lower portion of the water jacket 22 is provided with an opening 40 through the casing 10 which may normally be plugged, to drain the water from the jacket 22, when desired.

In operating my improved device the spring 18 is given the requisite tension for compressing the gas to the proper degree in the cylinder 11 before permitting the valve 17 to open and thus permit the compressed gas to pass into the condenser. The valve 25 may also by its adjustment cooperate to regulate the flow of the compressed gas into the condenser. The gas which commonly is

ammonia gas, although I may employ any gas which is adapted for use in refrigerating systems, is compressed in the cylinder 11 sufficiently to liquefy said gas, were it not for the heat developed by the compressing operation. Undue heating of the compressor cylinder 11 is prevented by the cooling water in the jacket 20. The compressed and heated gas on passing into the condenser 21 is effectively cooled by the cooling water in 75 the jackets 20 and 22 on account of the relatively large surface of the condenser and this action cools the gas sufficiently so that it is condensed into liquid form and collects in the bottom portion of the condenser, 80 where it is available for use in the remaining portion of the system.

From the above it will be observed that I have provided a construction in which a compressor and condenser are contained in 85 the same casing in such intimate association that maximum efficiency of operation may result. Also that all of the connections between the compressor and condenser are self contained and no outside fittings are required as a result of which leakage of the compressed gas is eliminated; also that the same cooling water is effective in cooling the compressor and condenser and furthermore that the same water jacket serves for 90 both the compressor and condenser and that the passageway from the compressor to the condenser is entirely waterjacketed.

While I have shown my invention in the particular embodiment above described, it 100 will be understood that I do not limit myself to this exact construction as I may employ equivalents known to the art at the time of the filing of this application without departing from the scope of the appended 105 claims.

What I claim is:

1. In a compressor, the combination of a cast metal casing having a cylindrical bore and integral annular walls surrounding said bore to form a condensing chamber and water jacket concentric with said bore, heads for enclosing said chamber and jacket, ports connecting said chamber and said bore, valve mechanism for preventing back-flow 110 through said ports, and means for compressing gas in said bore and forcing it through said ports into said chamber, said water jacket being in two annular portions, one within and the other outside of said chamber radially.

2. In a compressor, the combination of a cast metal casing having a cylindrical bore and integral annular walls surrounding said bore to form a condensing chamber and water jacket concentric with said bore, heads for enclosing said chamber and jacket, ports connecting said chamber and said bore, valve mechanism for preventing back-flow 120 through said ports, and means for compressing gas in said bore and forcing it through said ports into said chamber, said water jacket being in two annular portions, one within and the other outside of said chamber radially.

- ing gas in said bore and forcing it through said ports into said chamber, said water jacket being in two annular portions, one within and the other outside of said chamber radially, one of said heads being integral with said casing and enclosing said chamber and said inner and outer jackets at one end, a second of said heads being removable and enclosing said bore, said 5 chamber and said inner jacket at their other ends, and the third one of said heads enclosing said outer jacket at its other end at a distance from said second head, whereby a water jacket is formed between said 10 second and said third heads in communication with said outer jacket.
3. In a compressor, the combination of a cast metal casing having a cylindrical bore and integral annular walls surrounding said bore to form a condensing chamber and water jacket concentric with said bore, heads for enclosing said chamber and jacket, ports connecting said chamber and said bore, valve mechanism for preventing 15 back-flow through said ports, an enclosed crank case integral with said casing and below the same, a crank shaft in said case, a piston in said bore and devices connecting said piston and crank shaft, said water 20 jacket being in two annular portions, one within and the other outside of said chamber radially.
4. In a compressor, the combination of a central cylinder, annular walls surrounding said cylinder to form a condensing chamber and water jacket, heads for enclosing 25 said cylinder and chamber, ports connecting said cylinder and chamber, a check valve to prevent back-flow through said ports, and means for compressing gas in said cylinder and forcing it through said ports into said chamber, said water jacket being in two annular portions, one within and the other outside of said chamber radially. 30
5. In a compressor, the combination of a central cylinder, annular walls surrounding said cylinder to form a condensing chamber and water jacket, heads for enclosing said chamber, water jacket and one 35 end of said cylinder, ports connecting said cylinder and chamber, a check valve to prevent back-flow through said ports, and means for compressing gas in said cylinder and forcing it through said ports into said 40 chamber, said water jacket being in two annular portions, one within and the other outside of said chamber radially. 45
6. In a compressor, the combination of a central cylinder, annular walls surrounding said cylinder to form a condensing chamber and water jacket, heads for enclosing said chamber, water jacket and one 50 end of said cylinder, ports connecting said cylinder and chamber, a check valve to prevent back-flow through said ports, and means for compressing gas in said cylinder and forcing it through said ports into said 55 chamber, said water jacket being in two annular portions, one within and the other outside of said chamber radially, one of said heads enclosing said chamber and said inner and outer jackets at one end, a second of 60 said heads being removable and enclosing said cylinder, said chamber and said inner jacket at their other ends, and the third one of said heads enclosing said outer jacket at its other end at a distance from said second 65 head, whereby a water jacket is formed between said second and said third heads in communication with said outer jacket. 70

In witness whereof, I hereunto subscribe my name this 12th day of August, A. D. 1919.

ALF SELROD.
